UNITED STATES PATENT OFFICE.

HENRY A. FARLEY, OF HACKENSACK, NEW JERSEY, ASSIGNOR TO THE TAIT PAPER & COLOR INDUSTRIES, INC., OF HACKENSACK, NEW JERSEY, A CORPORATION OF NEW YORK.

PORTABLE DISPLAY OR SAMPLE BOOK.

Application filed July 2, 1924. Serial No. 723,812.

To all whom it may concern:

Be it known that I, HENRY A. FARLEY, a citizen of the United States, residing at Hackensack, in the county of Bergen and 5 State of New Jersey, have invented new and useful Improvements in Portable Display or Sample Books, of which the following is a specification.

This invention relates to portable display 10 or sample books particularly adapted for use in conveniently displaying samples of wall paper. By preference the improved portable display book will be used for samples of wall paper, but it will be understood that samples 15 of other material may be advantageous embodied in the improved book for display purposes.

One object of the invention is to provide 20 a portable display book having flexible covers and arranged to accommodate a comparatively large volume of material or display sheets of the same or varying sizes and with a novel form of binding or back-securing means for the sample leaves or components.

25 A further object of the invention is to provide a portable display book for samples of the character specified having a novel form of flexible handle attached to the back or binding portion of the book, and also 30 to associate with the opposite loose ends of the leaves and covers a securing means whereby the book during transportation may be preserved in proper shape and easily handled and rendered accessible.

35 With these and other objects and advantages in view, the invention consists in the construction and arrangement of the several parts which will be more fully hereinafter described and claimed.

40 In the drawings:

Fig. 1 is a perspective view of a portable sample book embodying the features of the invention.

45 Fig. 2 is a detail perspective view of a portion of the back of the book and a flexible handle and illustrating the preferred manner of applying the handle within the center of the back.

Fig. 3 is a section on the line 3—3, Fig. 1.

50 Fig. 4 is an end elevation of the book, showing an improved form of fastening means for the leaves and covers of the book.

Fig. 5 is a detail side elevation of a portion of the book, showing the fastening

means illustrated by Fig. 4 in separated relation.

Fig. 6 is a detail perspective view on an enlarged scale of portions of the covers for the book and the fastening means therefor of the same character as shown by Figs. 4 60 and 5.

Fig. 7 is a detail perspective view of portions of the covers of the improved book, showing modifications of the fastening means.

Fig. 8 is a perspective view of portions of the covers for the book, showing a further modification of the fastening means.

The numeral 5 designates front and rear flexible covers between which are arranged 70 a plurality of sheets or leaves 6 in the form of samples of wall paper or other material, which may be of the same or varying sizes or include borders or trimmings, the said covers 5 and leaves or sheets 6 being tightly 75 bound together at one end and having interposed therebetween relatively stiff binding strips or members 7, 8 and 9, through which are passed suitable fastening devices 10, said fastening devices being shown by dotted lines 80 in Fig. 1 and by full lines in Fig. 2. The leaves or sheets 6 have their edges coincident with the edges of the strips 7, 8 and 9, so as to produce a compact and neat appearance, the strips 7 and 9 being applied to the outer 85 sides of the bound ends of the leaves or sheets and the strip 8 disposed at an intermediate or central point relatively to the same ends of the leaves or sheets. Over the bound ends of the leaves or sheets and the 90 strips 7, 8 and 9 an outer finishing binding strip 11 is secured and may be of any suitable material, preferably fabric. The intermediate strip or binding member 8, as shown by Fig. 2, is formed with two rearwardly 95 opening transverse slots 12, the slots extending only partially through the transverse extent of the strip or binding member 8 so that the end walls of the said slots are located in advance of the front edge of the 100 strip 8, to provide seats for the flat ends 13 of a flexible handle or grip 14 of leather, canvas, or any other suitable material. The ends 13 are given a quarter turn, as at 15, so as to arrange the said ends in horizontal 105 positions for insertion in the rear open terminals of the slots 12 of the intermediate binding strip or member 8. The strip of

material from which the handle 14 is formed is about the same width as the slots 12 and of the same thickness as the strip or member 8, and the said ends 13 are inserted in the slots 12 and provide a flush fitting relatively to the said strip or member 8. When the ends 13 are inserted in the slots 12, fastening devices 16 are driven or inserted through the ends of the bound leaves or sheets and the members 7, 8 and 9 and openings 17 in the ends 13, and by this means the handle 14 is securely fixed in the bound end of the book. The handle 14 is disposed centrally with relation to the bound end of the book for balancing the latter when carrying the same, and by giving the strip forming the handle quarter turns as at 15, as above explained, the body of the handle engaged by the hand of the person carrying the book will present a flat surface for engagement of the hand, with material advantage in comfort to the carrier during transportation of the book. By having the strip forming the handle 14 of such dimensions as to flushly fit the slots 12 and the provision of the latter slots to receive the ends 13, a close regular binding assemblage is produced without irregular projections or distortions at the points where the handle ends are inserted in the bound end of the book. Though the particular manner of applying the handle to the book as above described is preferred, it will be understood that the handle ends 13 may be disposed in the bound end of the book by first inserting a chisel or analogous implement into this end of the book to form openings or seats for the handle ends and then applying the fastening devices 16.

As hereinbefore specified the covers 5 are flexible and with the leaves may be readily opened and turned back to fully display the various patterns embodied in the leaves or sheets, and during transportation of the book it is obvious that it is of material advantage to hold the free edges of the covers and leaves or sheets in close associated relation, so as to maintain the book in regular form and also prevent injury to the loose ends of the covers or leaves. For this purpose several different forms of fastening means are provided, and that shown by Fig. 1 consists in applying to the outer sides of the covers on opposite sides of the center opposed flexible fastening strips 18 and 19, the strips 18 carrying suitable sockets 20 and the strips 19 spring studs 21, as shown by Figs. 5 and 6. In the form of the fastening shown by Figs. 4, 5 and 6 the single strips 18 and 19 shown by Fig. 1 are replaced by doubled strips 22 and 23, which respectively carry the spring sockets 20 and studs 21 of the same form as those used in connection with the fastening shown by Fig. 1. The doubled strips 22 and 23 are secured against the outer and inner sides of the flexible covers 5. In Fig.

7 doubled fastening strips 24 are secured to one cover and have spring sockets 20 to engage studs 21 secured to the remaining cover. In the form of the fastening shown by Fig. 8 a doubled strip 25 is secured to and extends the full width of the one cover 5 and has a plurality of the spring sockets 20 to separably engage spring studs 21 secured to the remaining cover 5. These various forms of fastening devices are intended to illustrate that a flexible means of a strong and durable character may be used in either single or double and separable intermediately with relation to the loose ends of the covers and leaves or sheets, or extend from one cover fully across and separably connected to the remaining cover, either in strips disposed on opposite sides of the center of the loose ends of the covers and leaves or sheets or in continuous form, to fully protect or shield the ends of the covers and leaves or sheets.

It will be understood that the proportions of the covers and sheets may be varied in accordance with the requirements of the sample book and the character of the samples embodied therein, and under all conditions of modification as to proportions and dimensions the same essential features of the invention will be preserved, and which consist of a single carrying handle bound in the end of the book and of a flexible character, and flexible fastening means of a simple form applied to the free ends of the covers and leaves or sheets.

What is claimed as new is:

1. A portable display or sample book of the class specified, having flexible covers and leaves bound at one end with the covers, the bound end of the book having binding strips applied to the flexible covers and leaves in spaced relation, and a flexible handle having the ends inset and secured within the intermediate binding strip and held firmly between the bound leaves.

2. A portable display or sample book of the class specified, having covers and leaves bound together at one end and loose at the opposite end, the bound ends of the covers and leaves having binding strips associated therewith, and a flexible looped handle having its ends inserted and secured in the intermediate binding strip between the leaves, the handle being turned to provide a flat convenient grip means.

3. A portable display or sample book comprising flexible covers, leaves between said covers, a binding strip adjacent one end of each of the outermost leaves and a strip intermediate said leaves, fastening means extending through the leaves, covers and strips, the covers and leaves being free opposite their bound ends, and a flexible looped handle having its free ends turned in flat relation to and inserted in the inter-

mediate binding strip and secured by portions of the fastening devices at the center of the bound end of the flexible covers and leaves.

5 4. A portable display or sample book composed of flexible covers and leaves there-between and binding strips at the outer and intermediate portions of the leaves, fastening means extending through the binding 10 strips, covers and leaves, the intermediate binding strip on opposite sides of a point intermediate its ends being formed with slots extending partially transversely therethrough, and a flexible looped handle having 15 the ends thereof turned flat and inserted in the slots of the said strip and secured by portions of the fastening means.

5. A portable display or sample book having covers and leaves bound together with 20 outer and intermediate binding strips, fastening devices extending through the leaves, covers and binding strips, the intermediate binding strip having slots extending transversely partially through the same, and a 25 flexible handle of looped form having the ends turned flat and inserted in the slots of the intermediate strip and flush with the upper and lower sides of the latter so as to avoid bulk formation where the handle ends 30 are applied, a part of the fastening devices extending through the ends of the handle and tightly securing the latter to the bound end of the book.

6. A portable display or sample book comprising flexible covers and display leaves 35 closely assembled and bound at one end and having inner and outer binding strips extending the full length thereof, fastening means extending through the covers, leaves and binding strips, and a flexible handle of 40 looped form having the ends given a quarter-turn and inserted and secured in one of the binding strips with the opposite sides flush with one side of the strip, a part of the fastening means passing through the 45 ends of the flexible handle, the free looped portion of the handle providing a flat surface for convenience in gripping the same.

7. A portable display or sample book comprising covers and leaves bound together 50 at one of their ends, the opposite ends of the covers and leaves being normally free, a flexible handle inserted in the bound end of said book approximately midway between said covers, and separable fastening means 55 associated with the free ends of the covers, said fastening means comprising a member carried by one of said covers, flexible means connected to the free end of the other cover and foldable over the free ends of said leaves, 60 and said first-named cover, and a fastening member carried by said strip and engageable with said first-named member.

In testimony whereof I have hereunto set my hand.

HENRY A. FARLEY.
